UNITED STATES PATENT OFFICE.

EZRA T. MACINTYRE, OF RYE, NEW YORK, ASSIGNOR TO DEFIANCE SALES CORPORATION, OF NEW YORK, N. Y.

CALENDAR STAND.

Application filed October 6, 1923. Serial No. 666,920.

To all whom it may concern:

Be it known that I, EZRA T. MACINTYRE, a citizen of the United States, and a resident of Rye, New York, have invented certain new and useful Improvements in Calendar Stands, of which the following is a specification.

The present invention relates to improvements in the construction of stands for supporting loose leaves such as used on calendar pads and the like.

Stands of the same general character have been heretofore made of cast iron and have been provided with arched members for holding the leaves in place. Such arched members have been secured to the stands by movable locking devices such as a pivoted lever arranged to engage a kerf in the arch and in some cases the arch has been secured at another point by a lever which engages a horizontal portion of the arch. Cast iron stands are comparatively heavy and cannot be conveniently given a smooth finish without machining or polishing and are not well adapted for desk use because of their somewhat crude and cumbersome appearance. The locking devices heretofore used were mechanical movable elements which in devices of this class were not made to fine precision and it was therefore frequently extremely troublesome to engage or disengage the arch from the stand when it was desired to renew the loose leaves on the calendar or pad. My improved stand is formed of sheet metal which can be rolled so as to have a very smooth surface and which permits forming a stand of ample strength yet of much lighter weight than a cast iron stand of similar dimensions.

The provision of means for holding the arch in place on a sheet metal stand however presents problems not encountered in designing holding means for arches used on cast iron plates, one such problem being the provision of means for preventing the arch from "wobbling" that is from partaking of oscillatory movement. My improved stand is provided with means for detachably securing the arch to the stand without the use of movable mechanical devices and is also designed so that the arch when secured in place will not have any appreciable oscillatory movement with respect to the base.

An embodiment of the invention is illus-

trated in the accompanying drawings in which Fig. 1 is a plan view of a calendar stand with a portion of the calendar leaves broken away and the upper part of the arch sectioned off;

Fig. 2 is a vertical section on line 2—2 of Fig. 1;

Fig. 3 is a longitudinal section on line 3—3 of Fig. 2.

Referring in detail to the drawing the stand comprises a base indicated generally by numeral 10 which is formed of an upper leaf supporting portion 12 side flanges 14 and 16 and a rear flange 18 having integral curved bearing feet 20 which are curved or crowned as at 22 to present a smooth non-scratching surface to the support on which the stand rests. The forward edge of the portion 12 of the base is bent upwardly as shown in Fig. 3 to present a curved contact surface 24 to the desk or other support on which the stand is used.

An arch indicated generally by a numeral 30 is adapted to be sprung into and out of engagement with the base and this arch consists of uprights 32 and 34 which are united by a bridge portion 36 and uprights 38 and 40 which are continuations of the uprights 32 and 34 respectively.

The arch 30 is preferably made of a continuous rod of resilient material and is adapted to support the loose leaves 42 of the calendar or pad on either the right or left-hand side of the base. When used as a calendar the leaves are lifted and turned over the curved portion of the arch at regular time intervals.

The lower or free ends of the uprights 38 and 40 are notched as at 44 and 46 for engagement with the edges 48 and 50 of perforations 52 and 54 formed in the walls 56 of the member 58 which is spot-welded or otherwise secured as at 60 to the underside of the portion 12 of the base. The uprights 38 and 40 pass through perforations 62 and 64 formed in the top portion 12 of the base, these perforations being of substantially elliptical shape to form an elongated slot to permit the uprights 38 and 40 to be sprung so as to engage the notches 44 and 46 with the edges 48 and 50 of the ridge at number 58.

The bridge portion 36 of the arch rests on a lip 66 which projects downwardly and

forwardly over the portion 12 of the base. The base is cut away as at 68 so as to form offset seats 70 and 72 into which the uprights 32 and 34 can be sprung. The cut away portion is so formed that integral projections 74 are also provided which overlie the top of the bridge portion 36 of the arch.

The above construction permits the arch to be very readily secured to, or removed from the base. To remove it, it is merely necessary to spring the uprights 38 and 40 slightly to the left and raise them a trifle so as to disengage the notches 44 and 46 from the edges of the fixed member 58 whereupon they can be lifted and then the uprights 32 and 34 can be freely moved to the right and then forward a short distance so as to bring the bridge portion 36 clear of the projections 74 whereupon the entire arch can be lifted free of the stand. The loose leaves 42 can be removed and others substituted in their stead and then the arch can be secured by inserting the uprights 38 and 40 through the perforations 62 and 64, the bridge 36 of the arch at the same time being inserted in the opening 68 of the base and finally the uprights 32, 34, 38 and 40 being simultaneously or successively snapped in the position shown.

30 It will be observed that in Fig. 2 the uprights 38 and 40 are each supported near their lower ends at two spaced points namely by contact with the edges of the perforations 62 and 54 in the one instance and 35 the perforations 64 and 52 in the other instance. This means of supporting the arch is of importance when the base is formed of sheet metal because it prevents the arch from the "wabbling" which it would do if only supported by the latter passing through a thin wall of metal. By providing the member 58 having depressed portions 56 spaced away from the underside of the base the arch is supported at two elevations and therefore is prevented from oscillating or rocking in a direction perpendicular to his plane.

The above described arrangement provides an inexpensive yet effective means of 50 securing the arch to the stand and renders unnecessary the provision of any movable locking levers or the like such as employed heretofore in devices of this character.

Though I have described with great particularity of detail the specific embodiment of the invention illustrated it is not to be construed that I am limited thereby as various modifications may be made by those skilled in the art without departing from 60 the invention as set forth in the appended claims.

What I claim is:

1. A device of the class described comprising a base, an arch having all its uprights in the same plane, two of said up-

rights being united by a straight bridge portion and at least one of said uprights being notched near one end, a lip on the underside of said base extending below said bridge portion to prevent vertical displacement of the arch; said base having offset notches in juxtaposition to said lip forming seats for holding the uprights adjacent said bridge portion against horizontal displacement, said base also being perforated to receive the other uprights, and a rigid member secured to and spaced away from the underside of said base for receiving at least one of the last named uprights and adapted to prevent the arch from rocking in a direction transverse to its vertical plane.

2. A device of the class described comprising a base having a portion cut away to form a pair of offset seats, a downwardly and forwardly extending lip intermediate said seats forming a support, a second pair of seats formed by the edges of perforations in said base, a rigid member secured to the underside of said base and having openings in alignment with said perforations, forming seats spaced away from those formed by the perforations in the base, and an arch of resilient material adapted to yieldingly engage the said seats.

3. A device of the class described comprising a base having a portion cut away to form a pair of offset seats, a downwardly and forwardly extending lip intermediate said seats forming a support, a second pair of seats formed by the edges of perforations in said base, a rigid member secured to the underside of said base and having openings in alignment with said perforations forming seats spaced away from those formed by the perforations in the base, and an arch of resilient material having a plurality of uprights in the same plane two of which are joined by a bridge portion and others of which are notched for engagement with the seats formed on said rigid members.

4. A device of the class described comprising a pressed metal base, an arch formed of a resilient rod having four parallel uprights two of which are joined by a straight horizontal bridge portion and at least one of which is notched, a rigid member secured to and spaced from the underside of said base for engagement with at least one notched upright of said arch and means formed integral with said base cooperating with said bridge portion and the uprights adjacent thereto for holding the arch against either vertical movement or horizontal movement in a direction transverse to its vertical plane.

5. A device of the class described comprising a pressed base of light gauge material having a portion cut away to form offset seats and a lip intermediate said seats

but in a different plane than the latter, an arch adapted to be sprung into and out of engagement with said base and having a plurality of uprights two of which engage 5 said seats and are united by a bridge portion which engages said lip, and a member secured to the underside of said base and

having portions spaced away therefrom which are apertured to receive the ends of said uprights.

In witness whereof, I have hereunto signed my name.

EZRA T. MACINTYRE.
